Primary Examiner — Susan Moon Lee

(21) Appl. No.: **29/721,094**

CLAIM

(22) Filed: **Jan. 17, 2020**

(57)

The ornamental design for a mobile device accessory as shown and described.

Related U.S. Application Data

DESCRIPTION

(63) Continuation of application No. 29/605,903, filed on May 31, 2017, now Pat. No. Des. 876,436.

FIG. 1 is a first perspective view of an example mobile device accessory;

(51) **LOC (14) Cl.** **14-02**

FIG. 2 is a second perspective view thereof;

(52) **U.S. Cl.**

FIG. 3 is a front view thereof;

USPC **D14/420; D14/453**

FIG. 4 is a back view thereof;

(58) **Field of Classification Search**

FIG. 5 is a first side view thereof;

USPC D14/434, 447, 453, 432, 433, 385, 357,
D14/149, 457, 253, 251, 356, 242, 439, 344,
D14/140.2, 140.5, 140.9, 203.8, 209.1, 224.1,
D14/227, 229, 238, 440, 250-253, 203.5,
D14/203.3, 144; D13/108, 118, 199, 107, 177,
D13/119, 184; D3/218, 228, 269; D18/12, 4.4,
D18/4.5, 12.3; D8/349, 382; 361/683, 686,
361/679, 600, 679.44, 679.09, 679.26, 679.58;

FIG. 6 is a second side view thereof;

FIG. 7 is a top view thereof; and

FIG. 8 is a bottom view thereof.

The broken lines are directed to environment and are for illustrative purposes only. Broken lines of a particular embodiment form no part of the design claimed in that particular embodiment.
